Allen B. Wilson, Evanston, Ill., assignor to Acme Steel Company, Chicago, Ill., a corporation of Illinois

Application March 15, 1951, Serial No. 14,516

Term of patent 14 years

(Cl. D54—2)

To all whom it may concern:

Be it known that I, Allen B. Wilson, a citizen of the United States, residing at Evanston, in the county of Cook and State of Illinois, have invented a new, original, and ornamental Design for a Floor Plate, of which the following is a specification, reference being had to the accompanying drawing, forming a part hereof, in which:

Fig. 1 shows a top plan view of the floor plate, showing my new design;

Fig. 2 shows a vertical section taken on the line 2—2 of Fig. 1;

Fig. 3 shows a vertical section taken on the line 3—3 of Fig. 1;

Fig. 4 shows an edge elevation of the floor plate looking upwardly as viewed in Fig. 1; and

Fig. 5 shows a bottom plan view of the floor plate shown in Fig. 1.

I claim:

The ornamental design for a floor plate, as shown.

ALLEN B. WILSON.
